UNITED STATES PATENT OFFICE.

GEORGE M. PORTER, OF NEW YORK, N. Y.

PAD HOLDER.

Application filed December 3, 1927. Serial No. 237,362.

This invention relates to improvements in holders for calendar, writing or other memorandum pads, so constructed that they may be conveniently placed on a table or desk, and serve as a support for pens or pencils.

In various forms of calendars where a daily pad is attached thereto, a top plate is usually secured to the base of the pad and is utilized as a cutting device to sever the leaves of the pad. After a number of leaves have so been severed, the top plate no longer serves as a cutter, the result being that the remaining leaves when torn off, leave ragged edges and thus mar the appearance of the pad unless the said top plate is taken off and the stubs removed. This necessitates the expenditure of considerable time that might be utilized to better advantage.

In order to overcome these undesirable features, I have provided a pad holder, one of the objects of which is the provision of means associated with the said holder whereby the leaves may be readily and entirely removed from the pad without removing or disturbing any of the parts of the pad holder.

Another object of the invention is to provide a pad holder of the character referred to, the base of which, having means thereon to retain a loose leaf pad provided with grooves at the lateral edges thereof.

A further object of the invention is to provide a stamped metal supporting base for a pad of the character referred to, the said base being so formed as to provide means for angularly supporting the said pad.

A still further object of the invention is to provide a pad holder having combined pad retaining and pen or pencil supporting means thereon.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts

throughout the several views, and then finally pointed out and specifically defined and indicated in the appended claims.

Many changes can be made in the construction presently to be described, and many apparently widely different embodiments of my invention could be made without departing from the scope thereof. It is intended that all matters contained in the description or shown in the accompanying drawings shall be interpreted as illustrative and not in a limiting sense. It is also to be understood that the language used in the appended claims is merely intended to cover all the generic and specific features of the invention herein described, and all statements of the scope of the invention which, as a matter of language, might be said to fall therebetween, and that materials, sizes and relativities of parts are non-essential, except as called for in the claims.

In the drawings, forming a part of this specification,

Figure 1 is a side view in elevation of a pad holder embodying a preferred form of my invention.

Fig. 2 is a top plan view thereof, and

Fig. 3 is a section on line 3-3, Fig. 1, and

Fig. 4 is a fragmental sectional plan view showing a modified form of one of the post mountings.

Referring now to the drawings in detail, 5 indicates a supporting base preferably made of a single sheet of metal provided with a cupped or raised base strengthening portion 6 of approximately the same length and width as the pad 7 which rests thereon and with a supporting bracket 8 having an S or ogee contour in side elevation. The upper portion 9 and the lower portion 10 of the S, form surfaces or platforms upon which pens or pencils may be kept to be used when desired.

The base 5 is further provided with holes 100 or openings 11. Posts 12 having undercut portions 12^a, are rotatably mounted in the said holes. The pad 7 is a loose leaf pad comprising sheets 14, each of which is provided at their lateral edges and near one end 105 with notches 15 which form grooves 16, through which grooves the posts 12 pass to maintain the pad on the base 5. A top plate 17 provided with notches 18 overlies the pad 7 between the posts 12 and prevents acci- 110

dental displacements of the sheets 14. The posts 12 terminate in hooked ends 19 which provide means for supporting a pen or pencil 20, when in the Fig. 1 position. In shipping, the posts 12 are revolved to the position indicated in dot and dash lines, Fig. 2, the curved ends 19 acting to compress the pad and more securely hold the plate 17 in position.

10 To place a pad on the holder, all one has to do is to slightly flex the pad and place same between the posts 12 and the grooves 16 will engage the said posts and thus align the pad between them, or the posts may be 15 revolved until the hooked ends extend in a straight line outwardly and on each side of the base and the pad placed thereon with the grooves 16 in engagement with the said posts, after which the plate 17 may be 20 placed on the pad and the posts returned to the position shown in the drawings. After a sheet 14 has been used up, it is merely pulled out from between the posts, the 25 notches 15 in the sheets permitting of the said operation without tearing the sheet and leaving any stub under the plate 17.

In Fig. 4 I have shown a modified form of my invention wherein the reduced or undercut portion 12^a of one of the posts 12, 30 which journals in the opening 11, is eccentric with the post. This provides means for more firmly holding the pad when the posts are rotated to normal position after the insertion of a pad.

35 From the foregoing it will be seen that the device herein described makes a very simple, compact, inexpensive and attractive article in which it is easy to remove and re-

place the leaves of the pad when desired.

Having described my invention, what I claim as new and desire to secure by Letters Patent, is:

1. In a device of the character described, a base for supporting a pad, said pad having grooves at the lateral edges adjacent one end thereof, posts rotatably mounted in the base in engagement with the grooves for maintaining the pad on the base, and hooked ends on the posts providing pen-supporting means when extending beyond one end of the pad and providing pad-compression means when overlying the pad.

2. In a device of the character described, a base for supporting a pad, said pad having grooves at the lateral edges adjacent one end thereof, posts on the base for engagement with the said grooves for maintaining the pad on the base, and a plate removably supported on the pad between the posts to prevent accidental displacement of the pad sheets.

3. In a pad holder, a base for supporting a pad thereon, and rotatably mounted posts in the base for maintaining the pad on the base, one of the said posts being eccentrically mounted in the base.

4. A pad holder, comprising a base to support a pad thereon, pad maintaining posts rotatably mounted in the base, and hooked portions on the posts adapted to overlie the pad when rotated thereabove and prevent accidental displacement of said pad when being shipped.

In testimony whereof I hereunto affix my signature.

GEORGE M. PORTER.
